UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

CENTRIFUGAL CLEANER.

Application filed October 19, 1921. Serial No. 508,793.

My invention relates to centrifugal cleaners.

It has for its object to provide an improved centrifugal cleaner, and more especially to provide an improved and simplified centrifugal coal cleaner of compact form and great potential capacity which is adapted to clean sized coal while dry with such accuracy and speed as materially to reduce the cost of the cleaning operation. These and other objects and advantages of my invention will, however, hereinafter more fully appear.

In the accompanying drawings I have shown for purposes of illustration one embodiment which my invention may assume in practice.

In these drawings:—

Fig. 1 is a central vertical sectional view of this form of my invention.

Fig. 2 is a partial transverse section on line 2—2 of Fig. 1.

In this illustrative construction I have shown an improved refuse discharging means 1 and an improved cooperating coal delivering means 2, one movable relative to the other and adapted to receive coal to be cleaned from a suitable source of supply, herein a hopper 3 removably carried on the top of the member 1, and, after cleaning the coal in an improved manner, deliver the refuse separated therefrom to a suitable point, herein a chute 4, and the clean coal to another point, herein to a discharge passage 5 beneath the member 2, when the latter is rotated by suitable power connections hereinafter described and herein located beneath the member 1.

In my improved construction it will be noted that the member 1 is cylindrical and stationary, the same being carried upon a suitable support 6, and that within this member 1 is carried the rotary member 2 which is herein suitably attached as by a key 7 to a coaxially disposed upright shaft 8 which in turn has a reduced portion 9 on its lower end journaled in suitable adjustable thrust bearings 10 on an upstanding support, herein a casing 11, carried on the support 6, the member 2 preferably being hollow and provided with a hub 12 which is seated on the bearings 10 and in a corresponding hub 13 carried by the casing 11. As shown, the upper end of the shaft 8 is

also journaled in suitable roller bearings 14 55 carried in the bottom of the hopper 3, a sleeve 15 preferably being provided between the bearings and a reduced portion 16 on the upper end of the shaft, and the members 2 and 3 preferably being correspondingly 60 flanged and grooved as illustrated at 17 to prevent the entry of dirt into the bearings.

In my improved construction, it will be noted that the member 2 carries projections 18 on its upper end which move through passages 19 in the bottom of the hopper 3 and act to feed the material therein to chutes 20 formed by the hopper and cooperating surfaces on the members 18 and 2, the latter being provided with surfaces 21 and 22 70 which cooperate with a surface 23 on the hopper to provide a free passage for material beyond a flange 24 on the bottom of the hopper and onto a ring-like member or annular plate 25 preferably formed integral 75 with the member 2. Herein, the material is delivered to the member 25 at a point substantially midway between the edges thereof, and the member 25 herein has a downwardly and inwardly inclined material receiving surface adapted to receive the delivered material and through the rotation of the member 2 discharge the heavier material, such as slate or the like, outwardly over its upper edge through a lateral and then 80 downwardly extending outlet or chute 26 on the stationary member 1, while the coal, having less weight, slides inwardly down the inclined face of the member 25 and over its inner edge into another outlet or chute 27. 85

As shown, this chute 27 is preferably slightly enlarged and rounded at its mouth as at 28 and in turn delivers the partially cleaned material to a plate 29, similar to the plate 25, from which in turn the material passes 95 to a chute 30, similar to the chute 26, and a chute 31, similar to the chute 27, while the chute 31 in turn delivers to a plate 32, similar to the plate 25, from which the refuse material is delivered to a chute 33, similar 100 to the chute 26, and the clean coal to a chute 34, similar to the chute 27, the refuse chutes 26, 30 and 33 delivering onto the refuse discharge chute 4, while all of the clean coal discharge chutes 34 deliver to the discharge 105 passage 5, herein through an intermediate chamber 35 beneath the member 2 and above the casing 11.

My improved cleansing mechanism may obviously be driven in various ways, but the same is preferably driven through improved and simplified variable speed mechanism housed in the casing 11. In the present construction it will be noted that a friction disk 36 is suitably fixed as by a key 37 and nut 38 to the lower end of the shaft 8, and that a cooperating friction driving roller 39 is provided therefor, herein driven by a shaft 40 and adjustable longitudinally on a key way or spline 41 on that shaft by means of a suitable shipper or adjusting member 42 to vary the speed of rotation of the member 2 as desired. As shown herein, the shaft 40 is also journaled in suitable bearings 43 on opposite sides of the casing 11 and extends through the passage 5, the shaft also being journaled in a suitable bearing 44 in the wall of the member 2 and at a point external of the member 2, herein being provided with a worm gear 45 driven by a suitable worm 46 from a suitable source of power 47 which in a preferred form of my invention comprises an electric motor mounted on a bracket 48 integrally united with the member 1 and beneath the upper protruding end of the member 4.

In the operation of my improved construction, the coal to be cleaned, after screening to correct size, is delivered to the hopper 3, whereupon as the member 2 is rotated at the proper speed to give the desired centrifugal action, the speed herein being variable by adjusting the roller 39 relative to the disk 36, the projecting members 18 on the upper end of the member 2 cause the sized coal to be fed through the openings 19 in the bottom of the hopper 3 and into the chute 20 from which the material passes onto the annular plate 25, the refuse, such as slate or the like, being heavier than the coal, taking the outermost position thereon and accordingly being discharged by the plate 45 through the chute 26 into the refuse discharge 4, while the coal, being lighter, takes an inner position on the member 25 and through gravity passes into the chute 27 and so on through the machine, the successive cleaning stages similarly removing any slate or the like which may have been caught in the mass of partially cleaned coal and all the refuse being delivered to the member 4 while all the clean coal is delivered to the 55 passage 5.

As a result of my improvement, it will be observed that it is possible to eliminate the necessity for washing coal to clean it, my improved cleaner providing a satisfactory means for dry-cleaning the coal at a materially reduced cost. At the same time, it will be observed that my improved construction is exceedingly compact and not only has a large capacity but is capable of being made 60 for any capacity or coal size and operated

with a minimum of expense for power. Attention is also directed to the fact that the construction shown is exceptionally rugged and adapted to withstand long use with a minimum of attention, while due to its simplicity, the entire apparatus may be constructed at small expense, the only coal engaging surfaces which it is necessary to machine being the inclined surfaces of the members 25, 29 and 32. It should also be noted that if for any reason it is desired to obtain access to the interior of the mechanism, by simply removing the hopper 3 access may be had to the upper end of the member 2 including the bearings, while by simply removing the hopper 3 and by releasing the disk 36 the whole member 2 may be withdrawn if desired.

While I have in this application specifically described one embodiment which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a cleaning mechanism, a cleaning member rotating on a vertical axis having an inclined initial receiving surface on its periphery adapted to deliver material externally and internally, means for directly delivering material between the edges thereof by gravity feed, means for collecting material externally discharged therefrom and means for receiving material sliding inwardly thereon.

2. In a cleaning mechanism, a cleaning member rotating on a vertical axis comprising a series of superimposed inclined receiving surfaces adapted to deliver material externally and internally, and means for successively delivering thereto material to be cleaned including gravity feed delivering means directly delivering material at a point between the edges of the upper surface.

3. In a cleaning mechanism, a rotary cleaning member comprising a series of superimposed inclined receiving surfaces adapted to deliver material externally and internally, and means for successively delivering thereto material to be cleaned including delivering means initially delivering all material by gravity at a point between the edges of each surface.

4. In a cleaning mechanism, a rotary cleaning member having an inclined cleaning surface on its periphery from the external periphery of which heavy material is discharged centrifugally and over the internal periphery of which lighter material slides by gravity toward the axis of said rotating member, and a stationary member

enclosing said rotary member and having means for delivering material thereto and receiving refuse therefrom.

5. In a coal cleaning mechanism, a rotary cleaning member having a plurality of annular superimposed communicating inclined surfaces sloping toward the axis thereof, and a stationary casing in which said member rotates including a hopper communicating with the upper inclined surface and having discharge passages adjacent the upper edge of each surface.

6. In a coal cleaning mechanism, a rotary cleaning member having a plurality of annular superimposed communicating inclined surfaces sloping toward the axis thereof, and a stationary casing in which said member rotates including a hopper communicating with the upper inclined surface and having discharge passages adjacent the upper edge of each surface, said rotary member being accessible upon removal of said hopper.

7. In a coal cleaning mechanism, a rotary cleaning member having a plurality of annular superimposed communicating inclined surfaces sloping toward the axis thereof, a stationary casing in which said member rotates including a hopper communicating with the upper inclined surface and having discharge passages adjacent the upper edge of each surface, a refuse receiving means receiving the discharge from all of said discharge passages, and a separate clean material receiving means receiving the discharge from all of said inclined surfaces.

8. In a coal cleaning mechanism, a rotary cleaning member having a plurality of annular superimposed communicating inclined surfaces sloping toward the axis thereof, a stationary casing in which said member rotates including a hopper communicating with the upper inclined surface and having discharge passages adjacent the upper edge of each surface, a refuse receiving means receiving the discharge from all of said discharge passages, and a separate receiving means receiving the discharge from all of said inclined surfaces, said last mentioned means including an annularly disposed passage beneath the lower surface.

9. In a coal cleaning mechanism, a rotary

cleaning member having a plurality of annular superimposed communicating inclined surfaces sloping toward the axis thereof, a stationary casing in which said member rotates including a hopper communicating with the upper inclined surface and having discharge passages adjacent the upper edge of each surface, a refuse receiving means receiving the discharge from all of said discharge passages, a separate receiving means receiving the discharge from all of said inclined surfaces, said last mentioned means including an annularly disposed passage beneath the lowermost surface, and rotating means for said rotary member disposed beneath the same and within said annular discharge passage.

10. In a cleaning mechanism, a cylindrical stationary housing member having discharge passages in its periphery and a hopper above the axis thereof, a rotary cleaning member journaled in said housing member and having inwardly inclined communicating cleaning surfaces receiving material from said hopper and delivering heavy material to said discharge and lighter material toward the axis of said rotating member, and means disposed coaxially with said rotating member and within said stationary member for varying the speed of rotation of the former member as desired, said means including a housing between said mechanism and the clean material delivered from said inclined surfaces.

11. In a cleaning mechanism, a cylindrical stationary housing member having superimposed discharge passages in its periphery and a hopper above its axis, a rotary cleaning member journaled in said housing member and having a series of communicating superimposed inwardly inclined cleaning surfaces receiving material from said hopper and delivering heavy material to said discharge passages and lighter material toward the axis of said rotating member, and enclosed means disposed coaxially with said rotating member and within said stationary member for rotating the former member at different speeds.

In testimony whereof I affix my signature.
MORRIS P. HOLMES.
